UNITED STATES PATENT OFFICE.

ULYSSES SIDNEY SHOEMAKER, OF PRINCEWICK, WEST VIRGINIA, ASSIGNOR TO
GEO. W. WILLIAMS, OF BECKLEY, WEST VIRGINIA.

CHECK LOCK.

Application filed November 28, 1924. Serial No. 752,828.

To all whom it may concern:

Be it known that I, ULYSSES S. SHOEMAKER, a citizen of the United States, residing at Princewick, in the county of 5 Raleigh and State of West Virginia, have invented certain new and useful Improvements in Check Locks, of which the following is a specification.

This invention relates to locks, and more 10 particularly to locking hooks or the like.

The invention is especially designed for use in connection with mine cars, although it is not, of course, limited to such use.

In the mining of coal, it is the common 15 practice to give to each miner entering the mine, a number of checks which are usually in the form of small metal discs having a hole in them, adjacent the edge, by means of which they may be hung upon a hook 20 or the like. Each miner is assigned a number, and this number appears on each of the checks which he takes into the mine with him. When he has filled a car with coal, he hangs one of his checks on the 25 car by means of a suitable nail or hook, for the purpose of identifying the car as his, and so that the person charged with the duty of inspecting and dumping the cars 30 as they come out of the mine may know to whom to credit each car. As the cars are dumped, the checks are taken off and placed upon hooks on a "live-board," all checks bearing the same number being assembled upon the same hook. At the end 35 of the day, therefore, the number of checks on any given hook on the "live-board" represents the number of cars which that particularly miner has filled, and for which he will be paid. It is found in practice, 40 however, that frequently some unscrupulous miner will surreptitiously remove the check from a filled car belonging to his neighbor, and substitute his own check, thus depriving the rightful owner of credit for the car 45 of coal, and getting credit for it himself. In other words, it often happens that one miner thus "steals" a car of coal from another, while the car is standing on the track in the mine waiting to be hauled out. 50 This, as will be appreciated, gives rise to many disputes and controversies.

The primary object of the present invention, therefore, is to provide means for

preventing the unauthorized removal of a 55 check from a car after it has once been attached by the miner. To this end, the invention comprises a lock adapted to be secured to the car and having a hook or shackle movably mounted therein and projecting therefrom, on which hook or shackle 60 the check is hung. This lock is provided with a gravity controlled latch which is adapted to engage and hold the shackle in closed position, so long as the car remains substantially level, thus preventing removal 65 of the check, but it may be released when the car is tilted for dumping at the tipple. Thus, not until the car reaches its destination and is in the act of being dumped, can the lock be released and the 70 check removed.

A still further object is to provide auxiliary key-operated means for releasing the lock, in the event that the tipple man fails or neglects to remove the check at the proper time, and the car is restored to normal position. 75

In order that the invention may be readily understood, reference is had to the accompanying drawings, forming part of this 80 specification, and in which:

Figure 1 is a side elevation showing a conventional form of mine car and dumping apparatus therefor; 85

Figure 2 is a side elevation of one form of my improved lock, the wall of the casing being removed, and the shackle being shown in open position;

Figure 3 is a similar view showing the shackle in closed position, with a check supported thereon, and also illustrating the lock casing in a different angular position relative to the horizon; 90

Figure 4 is a vertical section on the line 4—4 of Figure 3; 95

Figure 5 is a horizontal section on the line 5—5 of Figure 3;

Figure 6 is a view of the check;

Figure 7 is a view similar to Figures 2 and 3, but showing a modified construction 100 of lock;

Figure 8 is a vertical section on the line 8—8 of Figure 7;

Figure 9 is a horizontal section on the line 9—9 of Figure 7; 105

Figure 10 is a horizontal section on an

enlarged scale, showing the engaging portions of the shackle and latch, as hereinafter described; and

Figures 11 and 12 are side and front views respectively, showing a shield which I may employ, if desired, in some cases.

Referring to the drawings in detail, a mine car of a common type is illustrated at A, and is shown in connection with a track 10 B, a chute C, and a tilting or dumping mechanism D. This need not be described in detail, but is so constructed as to tilt the car into an inclined position, as illustrated, so as to discharge its contents into the chute C. 15 This is a common method of unloading mine cars.

I propose to attach to the side of the car A, one of my improved locking hooks, the same being designated in its entirety by the 20 reference character E.

The locking hook comprises a casing consisting of a triangular frame 1 having front and back plates 2 and 3, secured thereto as by means of screws 4. Bolts 5 are provided by means of which the lock casing can 25 be secured to the wall of the car A.

Carried by the lock casing and movably mounted therein is a locking hook or shackle 6, integral with a straight shank 7, which 30 is constructed to slide through a keeper or guide 8, secured to the bottom of the casing. Formed in the upper surface of the shank 7, adjacent the keeper 8, is a notch 9, and the tail of the shank 7 beyond his notch 35 is preferably turned up, as illustrated at 10. Extending between this turned up tail 10 and a hook 12 set into the side wall of the casing, is a tension spring 11, which tends to urge the shank 7 and hook 6 outwardly into open 40 position, as shown in Figure 2. It will be understood that the free end of the hook or shackle 6 is arranged to register with and enter an opening 13, in the side wall of the lock casing when the hook is in its closed 45 or locked position, as shown in Figure 3. The hook is normally restrained from moving under the influence of the spring 11, by means of a swinging latch 14, pivoted at its upper end at 15 to a suitable cross-bar 16 or 50 the like, and extending in an inclined direction toward the bottom of the casing. The lower end of this latch 18 is shaped to engage with the notch 9 in the shank 7. Figure 3 shows the parts in locked position, with the lower end of the latch 14 engaging the notch 9. A slot 17 is provided in the lower part of the latch 14, through which slot the spring 11 extends. The spring therefore serves to 55 prevent lateral displacement of the latch 14.

60 The check 19, illustrated in Figure 6, is provided with a hole or opening 20 of such size as to freely slip over the hook 6. Such hook being in open position, as shown in Figure 2, when the empty car is sent into the 65 mine, the miner, when the car has been filled,

takes one of his checks bearing his identification number, and slips it over the hook 6. He then presses the hook inward until it reaches the position shown in full lines in Figure 3, and in this position, the hook will 70 be locked by means of the latch 14 engaging the notch 9, as described. When in this locked position, it is obvious that the check can not be removed from the hook or shackle 6.

When the car arrives at the tipple or other 75 dumping station, and is turned to the tilted or inclined position shown at the left, in Figure 1, the tipple man presses with his finger upon the hook or shackle 6, and forces it still further inward to the position shown 80 in dotted lines in Figure 3. This relieves the pressure of the spring on the end of the latch 18, and permits such latch to swing, by gravity, into the position shown in full lines in Figure 2, in which position it is clear 85 of the notch 9. Thereupon, when the shackle 6 is released, the spring 11 moves it outward to the open position shown in Figure 2, such outward movement being limited by engagement of the lower end of the latch 90 14, with the upturned tail 10 of the shank 7. After the hook or shackle 6 has thus been released and moved to open position, the tipple man removes the check in the usual manner and hangs it upon the "live-board." The 95 hook or shackle is permitted to remain in the open position, as the car is sent back into the mine for another load, and whatever miner receives this particular car, can, after 100 he fills it with coal, place his own identification check on the hook and lock it there by pushing the hook in again to the position shown in Figure 3.

Thus, it will be seen that I have provided gravity controlled means, governed by the angular position of the lock casing on car, relative to the horizon, for locking or releasing the check.

It may sometimes happen that the tipple man or other person charged with the duty 110 of removing the checks from the cars as they are dumped, fails to release the hook at the moment when the car is in its tilted position. If so, and the car is again righted, the check could not be subsequently removed, and this would give rise to considerable inconvenience.

In order to obviate this, and to take care 120 of any emergency of this nature which may arise, I have provided a small key-operated lock 21, such, for example, as a Yale cylinder lock, having a bolt 22 projecting toward the latch 14, and provided with the usual key-hole 23, accessible from the outside of the casing 1. In the event, therefore, of failure to release the hook or shackle when the car is in its tilted position, the tipple man, who is provided with a key for the lock 21, may, by inserting this key in the key-hole 23, and turning 125 130

it, project the bolt 22 and thus shift the latch 14 out of engagement with the notch 9, as indicated in dotted lines in Figure 3. This will release the shackle and permit the check to be removed. Therefore, while ordinarily the release of the shackle is controlled by gravity only, still, in the case of emergency, its release may be effected by means of a key.

10 While, in the arrangement so far described, the shackle and swinging latch are mounted for movement in the same plane, I have shown, in Figures 7 to 10, a modified construction in which the swinging latch is mounted to move in a plane at right angles to the shackle. Referring to these figures, the lock comprises a casing 1^a having a rear wall 1^b and a front wall 2^a. The hook or shackle 6^a is carried by a shank 7, extending transversely of the casing, and the hook 6^a, instead of being vertical, is preferably inclined as shown. The hook or shackle is urged toward open position by means of a leaf spring 11^a, secured at 25 one end to the case, as indicated at 11^b, and having its lower free end bearing against the up-turned tail 10 of the shank 7. The shank is confined and guided by means of a keeper 8^a, secured to the bottom of the 30 casing.

Interposed between the rear face 8^b of the keeper 8^a and the adjacent face of the up-turned end 10 of the shank 7 is the lower end of the swinging latch 14^a, pivotally mounted at its upper end on a transversely extending pin 15^a and positioned on such pin by means of suitable collars or the like, 35 15^b. The operation of this somewhat simplified modification will be apparent without further description. I desire to point out, however, that the meeting faces of the latch 14^a and the up-turned tail 10 are roughened or corrugated, as shown at 14^b in Figure 10. This is for the purpose of 40 preventing accidental displacement of the swinging latch by reason of shocks or jars to the car during the handling thereof. The spring 11^a holds these corrugated faces in firm engagement and, when the car is 45 tilted and it is desired to release the hook, said hook is pressed slightly backward into the casing and the latch will thereupon swing to one side clear of the shank 7, as shown in dotted lines in Figure 7. When 50 this occurs, the spring 11^a will force the hook outwardly to open position, the outward movement being limited in this case by engagement of the tail 10 with the 55 guide or keeper 8^a.

60 A key operated lock 21^a having a bolt 22^a, and provided with a key-hole 23^a, is mounted in the main lock casing and arranged to shift the latch 14^a, in cases of emergency, as described in connection with 65 the other figures.

Inasmuch as in this modification, the hook or shackle projects outwardly from the side of the car, it may be more liable to injury, and tampering. To protect the hook or shackle, therefore, I may secure to 70 the front face of the lock, a guard or shield such as shown at 24, in Figures 8 and 9. The purpose of arranging the hook 6^a in an inclined rather than in a vertical position is to enable this hood or shield to be 75 placed down closer to the hook. The object of having the hook inclined rather than horizontal is to insure that the check will always remain at that end of the hook adjacent the shank so that it will not drop off 80 when the hook is moved to open position.

In some cases, either with the arrangement shown in the first six figures or with that shown in Figures 7 to 10, it may be desirable to provide a swinging shield or 85 hood arranged to house or enclose the hook 6, and thus protect it from injury and from tampering by unauthorized persons. This is illustrated in Figures 11 and 12, in which the hood or shield is designated at 90 24^a and is shown as hinged to the wall of the casing at 25. In operating the lock so equipped, it is necessary to lift the shield with one hand, while the check is inserted or removed with the other. The shield 95 hangs by gravity in operative position, as shown, and thus conceals and protects the hook.

In either of the modifications shown and described, it will be seen that I have provided a hook or shackle and gravity controlled means for holding it in its closed or locked position, and with key-operated means for releasing it in case of emergency, and it is thought that the many 100 advantages of my invention will be readily appreciated by those familiar with such matters, without further discussion.

What I claim is:—

1. A check holder comprising a lock casing, a check supporting shackle carried by and projecting outside of said casing, said shackle being mounted for a rectilinear sliding movement to open and close the same, and means for holding the shackle closed 110 while the lock casing is in one position, and for permitting it to be manually opened when the lock casing is shifted to another position.

2. A check holder comprising a lock casing, a check supporting shackle carried thereby and movable to open and closed positions, a gravity-actuating swinging latch for holding the shackle in closed position, said latch being pivoted at its upper end, and having its lower end arranged to engage said shackle, means for normally restraining the latch from responding to the influence of gravity, and means for moving the shackle to open position when the latch swings by 120 125 130

gravity out of engagement therewith, after being released.

3. A check holder comprising a lock casing, a check supporting shackle carried thereby and movable to open and closed positions, a gravity-actuated swinging latch for holding the shackle in closed position, and a spring for moving the shackle to open position when said latch is released, said spring normally serving to restrain said latch from responding to the influence of gravity.

4. A check holder comprising a lock casing, a check supporting shackle carried thereby and movable from open position to closed position and beyond closed position to a third or release position, and a gravity-actuated swinging latch for engaging the shackle when in closed position so as to prevent it being moved to open position, said latch being releasable by moving the shackle to said third position.

5. The combination with a lock casing, a check supporting shackle movably carried thereby and constructed to open and close, means controlled by the angular position of the lock casing relative to the horizon for holding the shackle closed or permitting its manual release, and key-operated means

for releasing said shackle regardless of the angular position of the lock casing.

6. A check holder comprising a lock casing a check supporting shackle mounted in said casing for sliding movement to open or closed positions, said shackle having a hook-shaped portion projecting outside of the casing, the extreme end of said hook shaped portion being arranged, when in closed position, to cooperate with the outer wall of said casing to retain the check, gravity controlled means for holding the shackle in check retaining position, and a spring for moving the shackle, when released, into open position.

7. The combination with a dumping car, of a check holder therefor comprising a lock casing secured to the car, a check supporting hook projecting from the lock casing and movable to open and closed positions relative thereto, and means for holding said hook in closed position so as to prevent removal of the check so long as the car remains substantially level, and for permitting it to be moved to open position when the car is tilted.

In testimony whereof I affix my signature

ULYSSES S. SHOEMAKER.
